DESIGN FOR A COFFEE MILL HOUSING

Harry M. Jacobs, Brooklyn, N. Y., assignor to The Jacobs Bros. Co. Inc., Brooklyn, N. Y., a corporation of New York

Application February 25, 1937, Serial No. 67,835

Term of patent 3½ years

To all whom it may concern:

Be it known that I, Harry M. Jacobs, a citizen of the United States and residing at Brooklyn, county of Kings, and State of New York, have invented a new, original, and ornamental Design for a Coffee Mill Housing, of which the following is a specification, reference being had to the accompanying drawing, forming a part thereof, wherein:

Fig. 1 is a perspective view of the front portion of the coffee mill housing showing my new design, and

Fig. 2 is a perspective view of the rear of the housing shown in somewhat diminished scale and with the top and lower left hand drawer in open positions.

I claim:

The ornamental design for a coffee mill housing, as shown and described.

HARRY M. JACOBS.
